McKEE MHOON.
RADIATOR WATER GAUGE.
FILED MAR. 21, 1922.

UNITED STATES PATENT OFFICE..

McKEE MHOON, OF LINDSAY, CALIFORNIA.

RADIATOR WATER GAUGE.

Application filed March 21, 1922. Serial No. 545,479.

To all whom it may concern:

Be it known that I, MCKEE MHOON, a citizen of the United States, residing at Lindsay, in the county of Tulare and State of California, have invented certain new and useful Improvements in Radiator Water Gauges, of which the following is a specification.

My present invention relates to a gauge or indicator for denoting the liquid level in a motor vehicle radiator, and more particularly to a gauge simulating in its outline the configuration of the radiator to the cap of which it is secured and wherein a level indicator or target is employed and which is of such color as to fill the outline space of the indicator to the level corresponding to the level of the liquid within the radiator.

The objects of this invention are, primarily, to provide a construction of the float type, removable with the radiator cap, and wherein the steam of the fluid in the radiator is precluded from passing upwardly in the indicator and fogging the transparent sight openings, and at the same time affording an easy, free movement for the float or elevator. A further object is to provide a framed opening adapted for closing by a curtain or target carried by the elevator, and the upper edge of which extends transversely across the opening, denoting with the upper edge of the framed opening the level of the liquid within the radiator. Another object is to provide a balance spring within the float guide and to provide a normal adjustment for the float within the guide, adapting the installation to radiators provided with different head capacities. A further object is to provide a construction adapted for manufacture at a comparatively low cost, due to its simplicity and arrangement of parts, and one which is thoroughly efficient for the purpose designed.

With the above mentioned and other objects in view, the invention consists in the novel construction and combination of parts hereinafter described, illustrated in the accompanying drawings and pointed out in the claims hereto appended; it being understood that various changes in the form, proportion, size and minor details of construction within the scope of the claims may be resorted to without departing from the spirit

or sacrificing any of the advantages of the invention.

To more clearly comprehend the invention, reference is directed to the accompanying drawings, wherein—

Fig. 1 is a view in front elevation of one embodiment of my invention.

Fig. 2 is a vertical central sectional view taken on line 2—2 of Fig. 1.

Fig. 3 is a transverse sectional view taken on line 3—3 of Fig. 1.

Fig. 4 is a transverse sectional view taken on line 4—4 of Fig. 1.

Referring more particularly to the drawings, wherein like characters of reference designate corresponding parts—1 indicates the upper chamber of a vehicle radiator 70 mounting the usual filler cap attaching coupling 2, to which is detachably secured the radiator or filler cap 3 of the well known form. In its center, the cap 3 is provided with an opening 4 having a threaded interior 75 and within which is received the threaded central portion 5 of a tube 6 extending a considerable distance below the filler or radiator cap 3. In its side wall the lower end of the tube 6 is provided with fluid passages 7, and the lower end thereof is preferably closed by an adjustable sealing nut 8, formed with a boss 9 surrounded by the lower end of a coiled spring 10. Within the chamber 11 the tube 6 is a float 12 carrying a stem 13 extending upwardly in the tube, as in Fig. 2. Above the threaded portion 5, the tube is formed with a flange 14 adapted to rest on the upper surface of the cap or filler opening 3, and said tube is 90 locked within the opening 4 by a locking nut 15. The upper end of the tube is flattened or pressed to simulate the outline of a vehicle radiator 16 and the outline frame of the radiator is formed with a passage 15' 95 therethrough. The chamber 11 continues upwardly in the outline frame, as at 18, and the opposing faces of the opening 17 are closed by glass or other transparent members 19, each of which mounts a transverse line 100 or indication 20, in the present instance denoting the low or danger point of the fluid in the vehicle radiator.

At a point immediately above the upper surface of the radiator cap 3, the tube 105 wall 6 is surrounded by a collar 21

affording a finish thereto, and the collar and tube wall are provided with aligned vent openings 22, permitting the passage or escape of the steam which may enter the 5 chamber 11.

The stem 13 carries a baffle disk 23, which, under all conditions, lies above the upper surface of the vents or openings 22, and baffles or precludes the upward passage of 10 steam through the opening 18 to fog the glass 19. The upper end of the stem 13 mounts an indicating curtain or target 24 of an area co-extensive with the inner outline of the frame; said curtain being opaque 15 and preferably green in color to simulate water. The upper edge 25 of the curtain or target, dependent on the level of the water in the vehicle radiator, denotes in said radiator frame outline, the corresponding 20 level of the liquid in said vehicle radiator.

An air vent 26 is provided in the top of the frame 16.

It will be understood that the spring 10 25 affords a counterbalance for a portion of the weight of the float 12; stem 13; target or curtain 24 and baffle 23, and when the liquid level in the radiator is at a danger point, the weight of these parts is sufficient 30 to compress the spring until the edge 25 of the target or curtain aligns with the mark or line 20.

It will also be apparent that by employing the transparent members or glasses 19 35 and using a green curtain or target 24 having a horizontal upper edge, that the indicator will denote, in a color similar to water, the level of the liquid within the indicator, which is of a conventional radiator design.

I claim:—

1. In combination with an apertured radiator cap, liquid level indicating mechanism secured thereto and comprising a tube 45 provided with a fluid passage and extended

through said aperture and secured to the cap, said tube depending from said cap, a vertically adjustable member within the base of the tube, a slidable stem in said tube, a float secured to the lower end thereof, a gauge frame carried by said tube above the cap and extending laterally from opposite sides of the tube to overlie the cap, said frame being oblong in cross section and formed with a relatively large sight opening therethrough, a gauge glass closing the opposite sides of said opening and provided with a chamber therebetween communicating with the tube, and an indicator carried by said stem within said chamber 60 and adapted to extend across said sight opening for its full transverse length. 55

2. In combination with an apertured radiator cap, liquid level indicating mechanism secured thereto and comprising a tube 65 provided with a fluid passage and extended through said aperture and secured to the cap, said tube depending from said cap, a vertically adjustable member within the base of the tube, a slidable stem in said tube, 70 a float secured to the lower end thereof, a gauge frame carried by said tube above the cap and extending laterally from opposite sides of the tube to overlie the cap, said frame being oblong in cross section and formed with a relatively large sight opening therethrough, a gauge glass closing the opposite sides of said opening and provided with a chamber therebetween communicating with the tube, a counterbalance spring 75 for said float in the base of said tube and resting on said vertically adjustable member, and an indicator carried by said stem within said chamber and adapted to extend across said sight opening for its full 80 transverse length. 85

In testimony whereof I have signed my name to this specification.

McKEE MHOON.
